(57) **CLAIM**

I claim the ornamental design for a collapsible food cooler with split flap-like end curtains and attached scissors-type supporting stand, as shown and described.

DESCRIPTION

FIG. 1 is a perspective view of a collapsible food cooler with split flap-like end curtains and attached scissors-type supporting stand showing my new design;

FIG. 2 is a top plan view thereof;

FIG. 3 is an end elevational view thereof, the elevational view of the opposing end being identical thereto;

FIG. 4 is a bottom plan view thereof;

FIG. 5 is a side elevational view thereof, the elevational view of the opposing side being identical thereto; and,

FIG. 6 is a perspective view showing the collapsible food cooler with split flap-like end curtains and attached scissors-type supporting stand in use; the broken lines depict environmental structure for illustrative purposes only and form no part of the claimed design.
